CORRUGATOR

Walter J. Goetsch, Kenilworth, Ill., assignor to
 Samuel M. Langston Co., Camden, N. J., a corporation of New Jersey

Application February 24, 1934, Serial No. 712,722

7 Claims. (Cl. 154—31)

This invention relates to that type of machine for making single faced corrugated paper from a corrugated sheet and a surface sheet, in which the adhesive is applied in strips across the surface sheet at spaced intervals corresponding to the distance between successive crowns of the corrugated sheet, and the corrugated sheet and the surface sheet are progressively brought together with the adhesive strips in contact and in registry with the crowns of the corrugations of said corrugated sheet.

The desired registry of the adhesive applying mechanism in respect to the corrugating rollers cannot be secured with certainty when the machine is at rest due to back lash or lost motion in the gear train, which is taken up when the machine is started. Therefore, it has heretofore been necessary in making an adjustment to shut the machine down, make approximate adjustments, restart the machine, note the relative positions of the adhesive strips and the corrugations of the corrugated paper, and then shut down the machine and readjust the adhesive applying mechanism. Thus, a great deal of time has been wasted in effecting the proper adjustments.

One object of the present invention is to provide a mechanism for adjusting the adhesive applying mechanism in respect to the corrugating rollers while the machine is running, so that the strips of adhesive on the surface sheet will come directly opposite to or in registry with the crowns of the corrugated sheet while passing between the smooth surface roller and the corrugating roller.

As a feature of the present invention, I provide a rotatable roller having circumferentially spaced teeth meshing with the teeth of the adhesive applying roller, and also having a driving connection with said adhesive applying roller through the intermeshing teeth. This rotatable roller serves to force any excess of adhesive from between the teeth of the applying roller, and may also serve to transfer adhesive from a suitable source to the teeth of said applying roller.

In the accompanying drawing, there is shown for the purpose of illustration, one embodiment of the present invention. In the drawing:

Fig. 1 is a face view of a portion of a machine embodying my invention, certain gears being shown in section and the frame being shown in dot and dash lines.

Fig. 2 is a longitudinal section on the line 2—2 of Fig. 1 on a slightly larger scale, and

Fig. 3 is a sectional detail on a still larger scale of portions of the adhesive rollers.

55 The present invention is illustrated as adapted

to a machine designed for the manufacture of single-faced corrugated paper which may constitute the final product, or which may be delivered to another machine or portion of the machine to have an additional liner or facing sheet adhesive- 5

ly secured thereto.

In the specific form shown in the drawing, a sheet A to be corrugated is caused to pass between a pair of intermeshing corrugating rollers 11 and 12, each having the periphery thereof provided 10 with longitudinally extending corrugations including grooves and ridges. The corrugated paper is kept in contact with the periphery of the corrugating roller 12 along a portion of the periphery and passes between said roller 12 and 15 a smooth surface pressure roller 13, to press a liner or surface sheet B against the corrugated sheet.

Means are provided for applying adhesive directly to the surface sheet B in strips extending 20 across said sheet and spaced at intervals corresponding to the distance between successive teeth of the rollers 11 or 12, said means being spaced from the corrugating rollers 11 and 12 and the smooth roller 13. The sheet B is delivered from a 25 suitable supply roll or other source (not shown) and is passed over an idler 16 and then substantially in a horizontal direction into contact with the smooth surface pressure roller 13. The adhesive applying mechanism is disposed between 30 the pressure roller 13 and the idler 16 and includes an adhesive applying roller 17 disposed on the lower side of the traveling surface sheet B, and cooperating with a pick-up roller 18, the lower portion of which is immersed in a pan 19 35 containing silicate of soda or other suitable adhesive. Cooperating with the adhesive applying roller 17 and on the opposite side of the traveling surface sheet B there may, if desired, be provided a smooth surface freely rotatable pressure 40 roller 20 for pressing the sheet against the adhesive applying surface of said roller 17. In ordinary practice this roller 20 may be and preferably is omitted, but may be desired in some cases. In order that the adhesive be applied to the surface sheet B in strips extending across the sheet and spaced at intervals corresponding to the distance between successive teeth of the corrugating rollers 12, the roller 17 is provided with teeth 45 21, the spaces between said teeth being equal to 50 the distance between the successive teeth of the roller 12.

The roller 17 is driven in synchronism with the roller 12 so that the spaces between adjacent adhesive strips applied to the liner B will 55

correspond to the distance between the teeth on the roller 12. In the specific form shown, the drive for the roller 17 is from the shaft of the roller 12, the other roller being driven by the 5 intermeshing of the two rollers. The roller 12 carries on the shaft thereof a gear 23 meshing with a gear 26 which in turn meshes with a gear 27 mounted on the shaft of the roller 17. The gear ratios of these gears are such that the 10 peripheral speed of the roller 17 will be equal to the peripheral speed of the roller 12.

As a feature of the present invention, the pick-up roller 18 is provided with teeth on the surface thereof corresponding to the teeth 21 of the roller 17 so as to mesh therewith and be rotated by said latter roller. The pick-up roller 18 is thus driven at the same peripheral speed as the adhesive applying roller 17, and the intermeshing of the teeth prevents excess adhesive 20 from collecting on the sides of the teeth 21. The crowns of the teeth 21 are advantageously flat like those of ordinary gear teeth so that the strip C of adhesive which is to be applied to the surface sheet B will have a substantial width. 25 The intermeshing of the teeth limits the thickness of the strip.

The sheet B, after it has passed over the adhesive applying roller 17, travels around a portion of the periphery of the smooth surface pressure roller 13 and is pressed thereby against the crowns of the corrugated sheet passing therebetween.

I have shown the rollers 17 and 18 of the same size and smaller than the roller 12. This is not 35 essential as there is some advantage in regrounding the teeth or corrugations when they become worn, if all three rollers be of the same diameter.

As a feature of the present invention, means are provided for circumferentially adjusting the 40 roller 17 in respect to the roller 12, and if desired while the machine is running, so that the adhesive strips on the surface sheet B will surely come directly opposite to or in registry with the crowns of the corrugated sheet passing between 45 the corrugating roller 12 and the pressure roller 13. For that purpose, the gears 23, 26 and 27 have helical teeth and one of said gears, for instance the gear 27, is movable axially to cause the relative rotation of the rollers 12 and 17. As 50 shown the gear 27 is splined to the shaft of the roller 17 for axial movement therealong, and may be moved axially through the operation of a spindle 28 provided with a suitable operating handle 30 and screwed into the bracket 31 suitably supported on the frame structure of the machine. The spindle 28 is connected to one end of a lever 32 which is pivoted intermediate of its ends to the bracket 31 and swingable about its pivot by the rotation of the operating spindle 28. 55 The other end of the lever 32 is provided with a pin, projection or roller extending into a peripheral groove 34 formed in a collar 35 integral or otherwise connected to the gear 27. The circumferential adjustment of the adhesive applying roller 17 with respect to the corrugating roller 12 may be effected while the machine is running by turning the handle 30 and sliding the gear 27 endwise with its helical teeth engaging the helical teeth of the gear 26.

70 The regulation of the siliicate carried by the transfer roller 17 may be made by an eccentric bushing on the shaft of one of the rollers 17 or 18. As shown, the shaft of the pick-up roller 18 is eccentrically journaled in bearings or journal boxes 38 suitably supported in the frame

structure of the machine. These bearings 38 are provided with collars 40 having sockets extending radially from the peripheries thereof for receiving a suitable turning tool. If the roller 20 be employed pressure thereof against the transfer roller 17 may be similarly adjusted by eccentric journals or bushings 42.

In order to facilitate the threading up of the machine there is provided a series of fingers 43 supported on a rod 44 and spaced at intervals 10 therealong. These may extend from the adhesive applying roller 17 to the roller 13 and thence along the surface of the latter to near the point of tangency with the roller 12. They are shown quite long, but in practice they may be much 15 shorter and the adhesive roller 17 brought quite close to the roller 13.

It is desirable that the sheet A to be corrugated be heated before being pressed against the liner B in order to effect better adhesion between 20 the two sheets. For that purpose, the roller 12 is hollow to permit the delivery of steam there-through, through the bearings thereof. To supplement the heating effected by the steam in the interior of the roller 12, there is provided a 25 heater 45 in the form of a steam chest. This is adapted for receiving steam or suitable heating fluid therein, and extends lengthwise of the corrugating roller 12 in close proximity thereto. Said steam chest has a wall member 47 facing 30 the roller 12 and curved to follow the contour thereof so as to form a portion of the guide in threading up of the machine.

In order to strip the sheet from engagement with the roller 11 as said sheet passes beyond the 35 intermeshing portions of the two corrugating rollers 11 and 12, there is provided a series of transversely curved fingers 48 adjacent to the periphery of the corrugating rollers 12 and supported on the heater 45. These fingers 48 extend to or beyond the line of tangency of the pitch circles of the corrugating rollers 11 and 12 and into a series of circumferential grooves 50 in said roller 11 to insure proper stripping action. 40

In order to not bring the heater too close to 45 the lining sheet B with the stripes of adhesive thereon, the heater may be made narrower than is shown and have fingers at both edges instead of at only one.

The idler roller 16 is preferably vertically ad- 50 justable so that by raising the idler (assuming that the roller 20 be omitted) the paper may be lifted off the roller 17 particularly when threading up, and by lowering the idler the paper may be caused to press onto the roller 17 with any 55 desired degree of pressure dependent on the tension on the paper.

Having thus described my invention, what I 60 claim as new and desire to secure by Letters Patent is:

1. A machine for making corrugated paper, including means for corrugating an advancing sheet, means for applying adhesive to an advancing surface sheet in strips extending across said latter sheet and at spaced intervals there- 65 along, means for pressing the advancing adhesively coated sheet against the crowns of the advancing corrugated sheet, and means operable while the machine is running for adjusting said adhesive applying means with respect to 70 said corrugating means, whereby the adhesive strips of said surface sheet will move into registry with the corrugations of said corrugated sheet.

2. A machine for making corrugated paper, including a pair of corrugating rollers having 75

intermeshing teeth, and adapted to corrugate an advancing sheet therebetween, means for applying adhesive to an advancing surface sheet in strips extending across said latter sheet, and in spaced intervals therealong corresponding to the distance between adjacent teeth of said corrugating rollers, a smooth surface roller for pressing the advancing adhesively coated sheet against the crowns of the advancing corrugated sheet 10 as the latter passes over one of said corrugating rollers, and a heater adjacent to one of said corrugating rollers for heating the sheet after it is corrugated and before the surface sheet is applied thereto, said heater having projecting fingers for guiding the corrugated sheet along the surface of said last mentioned corrugating roller to a point of application of said surface sheet, said fingers extending adjacent to the line of tangency of the pitch circles of said corrugating 20 rollers.

3. A machine for making corrugated paper, including means for corrugating an advancing sheet, an adhesive applying elongated rotatable roller having teeth on the periphery thereof circumferentially spaced in accordance with the spacing of the corrugations of the corrugated sheet, and extending along substantially the entire length of said roller, said teeth being adapted to come successively into engagement with a traveling surface sheet to apply adhesive to said latter sheet in spaced transverse strips thereacross, a second roller having circumferentially spaced teeth meshing with said first mentioned teeth substantially throughout their entire length, 35 and having a driving connection with said adhesive applying roller through said intermeshing teeth, and means for pressing the adhesively coated sheet across the corrugations of said corrugated sheet.

4. A machine for making corrugated paper, including means for corrugating an advancing sheet, an adhesive applying elongated rotatable roller having teeth on the periphery thereof circumferentially spaced in accordance with the spacing of the corrugations of the corrugated sheet, and extending substantially along the entire length of said roller, said teeth being adapted to come successively into engagement with a traveling surface sheet to apply adhesive to said latter sheet in spaced transverse strips thereacross, a second roller having circumferentially spaced teeth meshing with said first mentioned teeth substantially throughout their entire length, and having a driving connection with said adhesive applying roller through said intermeshing teeth, means for applying adhesive to the teeth of said second roller to be transferred by said latter roller to the teeth of said adhesive applying roller, and means

for pressing the adhesively coated sheet against the crowns of said corrugated sheet.

5. A machine for making corrugated paper, including means for corrugating an advancing sheet, an adhesive applying elongated rotatable 5 roller having teeth on the periphery thereof circumferentially spaced in accordance with the spacing of the corrugations of the corrugated sheet, and adapted to come successively into engagement with a traveling surface sheet to apply 10 adhesive to said latter sheet in spaced transverse strips thereacross, a second roller having circumferentially spaced teeth meshing with said first mentioned teeth for removing excess adhesive from said latter teeth, said rollers having a 15 driving connection through said intermeshing teeth, and means for adjusting one of said rollers to vary the extent of intermesh between the teeth of said rollers.

6. A machine for making corrugated paper, including means for corrugating an advancing sheet, an adhesive applying elongated rotatable roller having teeth on the periphery thereof circumferentially spaced in accordance with the spacing of the corrugations of the corrugated 25 sheet, and extending substantially along the entire length of said roller, said teeth being adapted to come successively into engagement with a traveling surface sheet to apply adhesive to said latter sheet in spaced transverse strips there- 30 across, a second roller having circumferentially spaced teeth meshing with said first mentioned teeth substantially throughout their entire length for removing excess adhesive from said latter teeth, said rollers having a driving connection 35 through said intermeshing teeth, and eccentrically mounted bearings for one of said rollers for varying the extent of intermesh between the teeth of said rollers.

7. A machine for making corrugated paper, including means for corrugating an advancing sheet, an adhesive applying elongated rotatable roller having teeth on the periphery thereof circumferentially spaced in accordance with the spacing of the corrugations of the corrugated 40 sheet, and extending along substantially the entire length of said roller, said teeth being adapted to come successively into engagement with a traveling surface sheet to apply adhesive to said latter sheet in spaced transverse strips there- 45 across, and a second roller having circumferentially spaced teeth meshing with said first mentioned teeth substantially throughout their entire length, for preventing accumulation of adhesive between the teeth of said first mentioned 50 roller.
